Harold P. Norton.

UNITED STATES PATENT OFFICE.

HAROLD P. NORTON, OF WASHINGTON, DISTRICT OF COLUMBIA.

FORM OF LEADS, CRAYONS, OR PENCILS.

SPECIFICATION forming part of Letters Patent No. 445,252, dated January 27, 1891.

Application filed June 19, 1890. Serial No. 355,969. (No model.)

To all whom it may concern:

Be it known that I, HAROLD P. NORTON, a citizen of the United States, residing at Washington, in the District of Columbia, have invented an Improvement in the Form of Leads and Crayons for Pencils, Drawing-Instruments, and other Uses, of which the following is a specification.

My invention relates to an improvement in the shape of leads, crayons, or pencils, so that they may be quickly and easily pointed, the point to be always of uniform width for the same lead, crayon, or pencil.

The object of my invention is to make the lead of such a form that by cutting it on a plane oblique to its axis a point of the desired width will be formed which shall retain as much of the original outer covering of the lead, crayon, or pencil as possible. I attain these objects by the shape of the lead, crayon, or pencil, as illustrated in the accompanying drawings, which illustrate some of the forms that may be used.

Figure 1 is a front elevation of a lead, crayon, or pencil. Fig. 2 is a side elevation of a lead, crayon, or pencil; Fig. 3, a cross-section of Figs. 1 and 2. Fig. 4 is a front elevation of a lead, crayon, or pencil. Fig. 5 is a side elevation of a lead, crayon, or pencil. Fig. 6 is a cross-section of Figs. 4 and 5. Fig. 7 is a front elevation of a lead, crayon, or pencil. Fig. 8 is a side elevation of a lead, crayon, or pencil. Fig. 9 is a cross-section of Figs. 7 and 8. Fig. 10 is a front elevation of a lead, crayon, or pencil. Fig. 11 is a side elevation of a lead, crayon, or pencil. Fig. 12 is a cross-section of Figs. 10 and 11. The above drawings show the different views of pencils with curved and plane sides with points of different widths. Figs. 13 and 19 and 23 and 25, inclusive, are cross-sections on a larger scale, showing some of the shapes that may be used. Fig. 20 shows a pencil fitted with an improved movable lead. Fig. 21 shows a front and Fig. 22 a side elevation of the pencil-point of a drawing-instrument fitted with an improved lead.

Similar letters refer to similar parts throughout the several views.

The shape of the lead, crayon, or pencil is such that when cut by the oblique plane the

side C will form the point, the sides B being cut away, so that the point will be tapered on its sides and the side A an arc of a circle or a straight line depending upon the use of the 55 lead, crayon, or pencil. The width of the side C determines the breadth of the point, as for very fine points it will be formed by the intersection of the two sides B, as shown in Figs. 13, 17, and 23, and for broader points it 60 will be of varying widths, as shown in the other figures. The sides A and C may be arcs of the same circle, but if the point is to be very broad the side C may be a straight line, as in Fig. 16, or if the point is to be very 65 fine the side may be the intersection of two lines. The sides B may be curves, as shown in Figs. 3, 6, 13, 14, 15, and 16. Straight lines, as shown in Figs. 9, 12, 17, 18, 19, 23, and 25, or double curves, as shown in Fig. 24. 70

What I claim as my invention, and desire to secure by Letters Patent, is—

1. A lead, crayon, or pencil of such a form that a section at right angles to its axis will be a polygon two of whose sides are arcs of 75 the same circle, whose center is within the polygon, and two of whose sides are arcs of external circles, curves, straight lines, or a combination of curves and straight lines, such that when the lead, crayon, or pencil is cut 80 by a plane oblique to its axis the sides and the oblique plane will form a point of the desired width, substantially as set forth.

2. A lead, crayon, or pencil of such a form that a section at right angles to its axis will 85 be a polygon one of whose sides is the arc of a circle whose center is within the polygon, and two of whose sides are arcs of external circles, curves, straight lines, or a combination of curves and straight lines, which arcs 90 of the external circles, curves, straight lines, or combination of curves and straight lines shall intersect at an angle, so that when the lead, crayon, or pencil is cut by a plane oblique to its axis the sides and the oblique 95 plane will form a fine point, substantially as set forth.

3. A lead, crayon, or pencil of such a form that a section at right angles to its axis will be a polygon one of whose sides is an arc of 100 a circle whose center is within the polygon, the side opposite the arc a straight line, and

two of whose sides are arcs of external circles, curves, or straight lines, or a combination of curves and straight lines, so that when the lead, crayon, or pencil is cut by a plane 5 oblique to its axis its sides and the oblique plane will form a point the width of the side opposite the arc, substantially as set forth.

4. A lead, crayon, or pencil of such a form that a section at right angles to its axis will 10 be a polygon whose sides are straight lines, and which if it has more than three sides those which are opposite and parallel shall not be of the same length, so that when the lead, crayon, or pencil is cut by a plane oblique to its axis its sides and the oblique plane 15 will form a point of the desired width, substantially as set forth.

5. A lead, crayon, or pencil of such a form that a section at right angles to its axis will be a polygon, (other than a regular rectangle with equal sides or a regular hexagon,) the sides of said polygon to be formed of arcs of circles, curves, straight lines, or combination of curves and straight lines, so that when the lead, crayon, or pencil is cut by a plane oblique to its axis its sides and the oblique plane 20 will form a point of the desired width, substantially as set forth. 25

In testimony whereof I affix my signature in the presence of two witnesses.

HAROLD P. NORTON.
